UNITED STATES PATENT OFFICE.

WILLIAM KELSO, OF PITTSBURGH, PENNSYLVANIA, ASSIGNEE TO THE McCONWAY & TORLEY COMPANY, OF PITTSBURGH, PENNSYLVANIA, A CORPORATION OF PENNSYLVANIA.

CAR-COUPLING.

1,239,187.

Specification of Letters Patent.

Patented Sept. 4, 1917.

Application filed June 8, 1917. Serial No. 173,565.

To all whom it may concern:

Be it known that I, WILLIAM KELSO, a citizen of the United States, residing at Pittsburgh, in the county of Allegheny and 5 State of Pennsylvania, have invented certain new and useful Improvements in Car Couplings; and I do hereby declare the following to be a full, clear, and exact description of the invention, such as will enable others 10 skilled in the art to which it appertains to make and use the same.

My invention relates to the construction of car couplers for railway vehicles and particularly to couplers which are designed to 15 be especially suited for application to passenger cars.

Generally stated, the object of the invention is to produce a car coupler of the pivoted head type which shall be strong, durable, compact, and easily assembled, and in 20 which the component members or elements are so combined and related that the various operations of the mechanism, and particularly the operation of throwing the knuckle 25 open, may be readily and efficiently performed. This object is attained by the employment of certain structural features and combinations of features which will be hereinafter pointed out and claimed, the principal ones being certain relationships between the coupler knuckle, its locking mechanism, the pivoted stem and the upright knuckle-opener lever for coöperating with the knuckle tail to effect an opening rotation 30 of the knuckle when the locking mechanism is caused to perform an extended unlocking movement.

In the drawings illustrating the preferred embodiment of my invention, the scope 40 whereof is pointed out in the claims,

Figure 1 is a plan view of a car coupler embodying the invention, a portion of the coupler stem and portions of the uncoupling mechanism being omitted.

Fig. 2 is a horizontal central section of the coupler, the knuckle being shown in plan.

Fig. 3 is a side elevation of the mechanism shown in Fig. 1, a portion of the coupler head being broken away to disclose the 50 coupler locking mechanism.

Fig. 4 is a transverse section on the line 4—4, Fig. 2.

Fig. 5 is a section on the line 5—5, Fig. 1.

Fig. 6 is a detail view showing in elevation the lock for the knuckle and the associated 55 device for preventing accidental unlocking of said lock.

Fig. 7 is a detail perspective view of the coupler lock.

Fig. 8 is a detail perspective view of the 60 device for locking the lock against accidental unlocking.

In the drawings the coupler head is indicated by the numeral 1, the knuckle, which is pivotally mounted on the head by a 65 knuckle pin 2, is indicated by the numeral 3, while 4 indicates the lock for the knuckle and 5 is the knuckle-opener lever by which the knuckle may be rotated to open position.

The coupler head 1 is pivotally connected 70 to the coupler stem, as for example by means of the pivot pin 6, and is preferably composed of upper and lower spaced plates or bars 7 which are adapted to have mounted thereon a mechanism for centering the 75 coupler head 1 with respect to the stem, a suitable form of such centering mechanism being described in my Patent No. 950,485, issued March 1, 1910.

The tail of the knuckle 3 is preferably 80 provided upon its upper and lower surfaces adjacent to its inner end with lugs or shoulders 8 and 9, respectively, which are adapted to engage corresponding rearwardly facing lugs or shoulders 10 and 11 upon the interior 85 of the coupler head when the knuckle is in closed position. In order to permit an upright knuckle-opener lever 5 to be employed to perform effectively the function of rotating the knuckle to open position, the lugs or 90 shoulders 8 and 9 upon the knuckle tail are located well to the rear of the knuckle pin 2 so that the corresponding lugs or shoulders 10 and 11 formed on the interior of the coupler head in advance of the said lugs 95 8 and 9 may be disposed sufficiently far rearwardly to allow an upright knuckle-opener lever 5 to be pivotally mounted upon the knuckle side of the coupler head 1 to the rear of the Master Car Builders contour 100 line regulating the configuration of the forward portion of the coupler head 1. As well shown in Figs. 2 and 4 of the drawings, when the parts are in locked position the lower arm of the upright bell-crank lever 105 5 is housed in a pocket or recess 12 formed

in the coupler head 1.

in the coupler head 1 and opening toward the knuckle tail. The upper portion of the knuckle-opener lever 5 operates within a housing 13 which, as clearly shown in Figs. 1 to 5, inclusive, is open toward the guard-arm side of the coupler head. The knuckle-opener 5 is pivotally mounted upon a pin 14, which extends longitudinally through suitable perforations in the upwardly extending walls of the housing 13 above the upper knuckle pivot lug 15 of the coupler head. By thus disposing the pivot pin 14 the replacement of a worn or broken knuckle-opener with a new one is facilitated and the integrity of the pivotal mounting of the knuckle-opener may be readily observed, as will be appreciated by those familiar with the art.

In order that the length of the coupler head 1 may not require to be increased to accommodate the knuckle 3 without interfering with the stem of the coupler, the parts are preferably so related that the tail of the knuckle is adapted to overlap and swing between the plates or bars 7 constituting the stem. This enables the pivot pin 6 to be positioned farther forwardly than would otherwise be possible and consequently permits a decrease in the longitudinal dimension of the coupler head 1.

The face 16 of the knuckle tail which engages the lock 4 is preferably parallel to the longitudinal axis of the coupler head 1 when the knuckle is in locked position, the force communicated to said lock from said knuckle during pulling being thus directed transversely of said coupler head. The abutment or lock engaging face 17 on the coupler head for resisting the lateral thrust of the lock 4 is also preferably parallel to the longitudinal axis of the coupler head. Instead of being formed with a recess or pocket to receive the lower end of the knuckle-opener lever 5, the rear face 18 of the tail of the knuckle is formed as a continuous surface sloping without abrupt turns or angles from the inner end of the knuckle tail forwardly and toward the guard-arm side of the coupler head and merging with the periphery of the hub 19 of the knuckle. This construction not only results in making the knuckle tail of wedge-like shape preventing the knuckle 3 from being pulled out of the coupler head should the knuckle pin 2 be broken in service, but it also has the advantage of allowing the knuckle-opener lever 5 to engage the rear of the knuckle tail at a point insuring an efficient application of power thereto by an upright-bell-crank knuckle-opener, as well also as the advantage of minimizing the grinding action between the knuckle-opener and the knuckle tail.

The lock 4 that is preferably employed is of the following nature: It is provided with

an extension 20 which projects downwardly through the lower wall of the coupler head. On the rear side and near the lower end of this projection is a shoulder 21 which is adapted to be seated upon a co-operating 70 lock-set seat or shoulder 22, to thereby support the lock 4 in raised or lock-set position. Formed in the lock 4 and opening through the top and rear walls thereof is a recess 23 that receives a member 24 by 75 which the lock may be connected to the uncoupling lever 25 and which also serves as a lock-to-the-lock for preventing the lock 4 from accidentally jarring to unlocked position while the coupler is in service. The member 24 is provided with a rearwardly extending lug 26 which is adapted to extend under the surface or shoulder 27 on the interior of the coupled head when the lock 4 is in locked position. Until the lug 26 is 80 withdrawn from beneath the locking shoulder 27 the lock 4 cannot be raised. This withdrawal of the lug 24 from beneath the shoulder 27 to permit the lock 4 to be unlocked is accomplished by the uncoupling 85 lever 25 whose initial uncoupling movement causes the member 24 to be drawn upwardly in the recess or pocket 23 of the lock until the lock-to-the-lock projection 26 clears the co-operating shoulder 27 on the coupler head. 90 Thereafter the continued upward pull of the cranked uncoupling lever 25 upon the member 24 causes the lock 4 to execute an upward movement sufficient either to unlock the knuckle 3 or to actuate the knuckle-opener lever 5 after the knuckle has been unlocked, as the case may be. When the lock 4 has returned to locked position the member 24 slides down the inclined lower wall of the lock recess 23 and the locking nut 195 26 is projected beneath the locking face or shoulder 27 on the coupler head 1.

At its upper end and toward its forward face the lock 4 is provided with a laterally extending lug 28 which is adapted to engage the short arm 29 of the upright bell-crank lever 5, and thereby cause a knuckle-opening rotation of said lever upon its pivot pin 14. The lug 28 rests upon the top wall of the coupler head when the parts are in locked position, as well shown in Fig. 4, thus supporting the lock 4 and limiting its downward movement; and because the location of the lug 28 at the top of the lock permits a minimum clearance above the latter to suffice for the performance of an extended unlocking movement sufficient to rotate the knuckle-opener 5 and open the knuckle 3, a vertically sliding lock and an upright bell-crank knuckle-opener lever 125 operated thereby may be employed practically in couplers designed to be applied beneath the platforms of passenger cars.

When the lock 4 is lifted it is suspended on the member 24 in such relation to its 130

center of gravity as to cause the lock-set shoulder 21 thereof to move over the lock-set seat 22 upon the coupler head. The rearward movement of the lock to bring about the engagement of the lock-set shoulders is also positively effected by the contact of the lug 28 of the lock with the upper arm 29 of the knuckle-opener 5, the location of the lug 28 toward the forward face of the lock 10 causing the downwardly extending leg 20 to tip or swing rearwardly when the lug 28 is pulled upwardly against the knuckle-opener lever 5 while the knuckle 3 remains in closed position.

15 As shown clearly in Figs. 4 and 6 the lower face 30 of the lock 4 inclines upwardly toward the knuckle 3. When the knuckle rotates outwardly after the lock has been set in lock-set position the tail of the knuckle 20 engages the inclined surface 30 and disengages the lock-set shoulder 21 from the lock-set seat 22 upon the coupler head. The lock 4 rides upon the tail of the knuckle until the knuckle 3 is fully closed when the 25 lock drops to locked position.

The uncoupling mechanism illustrated in the drawings, and which it is preferred to employ for actuating the lock 4, is fully illustrated and described in the Joseph Kelso and William Kelso Patent No. 30 1,032,066, issued July 9, 1912. The uncoupling lever 25 of this mechanism is journaled in a plate or bracket 31 which is pivotally mounted upon the upper face of the 35 coupler head 1 by means of the pivot pin 6 that connects the coupler head to the coupler stem. The uncoupling lever 25 is rotatable in the journals of its supporting bracket to actuate the lock 4.

40 I claim:

1. In a car coupler, the combination with a coupler head, of a knuckle pivotally mounted thereon, a lock for said knuckle, and a knuckle-opener device mounted on 45 said coupler head, said lock having a lug adapted to engage and actuate said knuckle-opener device, said lug being adapted to engage the top wall of the coupler head to support said lock when in locked position.

50 2. In a car coupler, the combination with a coupler head, of a knuckle pivotally mounted thereon, a vertically sliding lock for said knuckle projecting upwardly through the coupler head, and a bell-crank knuckle 55 opener lever having its upper arm projecting above said lock, said lock having a lug which extends outside of said coupler head when the parts are in locked position and which is adapted to engage and actuate said 60 knuckle opener lever.

65 3. In a car coupler, the combination with a coupler head provided with a knuckle receiving recess, of a coupler stem extending into a rearwardly open socket in said head and pivotally connected thereto, a knuckle

rotatably mounted on said head, and means for locking said knuckle in coupled position, the tail of said knuckle being adapted to overlap a portion of said stem, and said stem receiving socket forming a continuation of 70 the knuckle receiving recess of said head.

4. In a car coupler, the combination with a coupler head provided with a knuckle receiving recess and with a coupler stem receiving socket, of a coupler stem involving 75 spaced members extending into said socket and pivotally connected to said head, a knuckle pivotally mounted on said head, and means for locking said knuckle in coupled position, said socket forming a continuation of 80 said knuckle receiving recess, and a portion of the tail of said knuckle being adapted to pass between said spaced members.

5. In a car coupler, the combination with a coupler head, of a knuckle and a coupler 85 stem both of which are pivotally connected to said head, and a lock for retaining said knuckle in coupled position, said knuckle being provided with a hub and having a vertical lock-engaging face normally extending longitudinally parallel to the line of draft and having its rear wall sloping forwardly toward the guard-arm side of 90 said coupler head and merging with the hub of said knuckle, and said coupler head 95 being provided with an abutment for supporting said lock against the forces communicated thereto by the knuckle, said lock-engaging face of said knuckle and said abutment on said coupler head being in advance 100 of the axis of the pivotal connection of said head and stem and being upon opposite sides of the longitudinal axis of said head passing through said pivotal axis.

6. In a car coupler, the combination with 105 a coupler head, of a knuckle, a lock for said knuckle, and an upright knuckle-opener lever, said knuckle having a hub and a tail gradually increasing in width from said hub rearwardly to the lock engaging face of said knuckle, the rear face of said knuckle tail sloping without abrupt change of direction from the inner end of said tail forwardly toward the guard arm side of the coupler head and merging with said hub, 110 and the lower portion of said knuckle-opener lever engaging and co-operating with said sloping rear face of said knuckle tail to rotate the knuckle to open position.

7. In a car coupler, the combination with 115 a coupler head formed upon its knuckle side with a pocket adapted to receive the lower arm of an upright bell-crank knuckle-opener lever, of a knuckle having a tail formed with a rear face which slopes forwardly 120 toward the guard arm side of said coupler head, and an upright bell-crank knuckle-opener lever pivotally mounted on said coupler head and having a lower arm which engages said sloping face of said knuckle 125 130

tail and is adapted to extend into said pocket in said head when the knuckle is in locked position.

8. A coupler head having upper and lower pivot lugs adapted to receive the hub of a coupler knuckle between them, and having rearwardly facing shoulders on the upper and lower walls of said head adapted to co-

operate with a knuckle having corresponding shoulders formed on the tail thereof, and having pivot pin openings and a recess to the rear of said shoulders adapted to receive the forward end of a coupler stem.

In testimony whereof I affix my signature.

WILLIAM KELSO.
